UNITED STATES PATENT OFFICE

2,001,163

TRAIN-CONTROL APPARATUS

Frank J. Sprague, New York, N. Y., assignor to
General Railway Signal Company, New York,
N. Y., a corporation of New York

Original application December 31, 1914, Serial
No. 879,939, now Patent No. 1,780,148, dated
October 28, 1930. Divided and this application
August 24, 1927, Serial No. 215,119. In Canada
December 29, 1915

41 Claims. (Cl. 246—63)

This application is filed as a division of my prior application filed December 31, 1914, Ser. No. 879,939, now matured into U. S. Letters Patent No. 1,780,148, granted October 28, 1930, for method and apparatus for control of train movement, and the subject-matter hereof forms a part of the apparatus disclosed in the aforesaid prior application.

The object of my present invention is to provide suitable automatic and track actuated devices associated and cooperating with standard braking equipment, for example, the Westinghouse valve by means of which the brake pipe of the braking system may be automatically vented without interference with further and additional venting thereof through the usual manual means.

A further object of my invention is to provide means whereby the engineer of a train may through proper action forestall or modify the actuation of the automatic braking equipment.

Another object is to provide means in combination with the forestalling means for automatic resetting, without track impulse, of the brake initiating means.

25 Other objects of my invention will appear from the following specifications and claims.

The automatic air brake system upon which my invention is herein shown as superimposed, is the ordinary form embracing what is known as the Westinghouse G6 engineer's valve, this valve being chosen for simplicity of illustration and without intended limitation. It comprises the following elements:

(a) One or more main reservoirs of large capacity carried on the locomotive, in which is normally maintained a volume of air under high pressure, varying on different equipments from 90 to 130 pounds, which air is supplied by an automatically controlled steam or electric pump.

(b) A pipe system consisting of air pipes individual to each car, joined continuously from car to car by detachable flexible hose couplings, this system being supplied with pressure air from the main reservoir through a feed valve by which the air therein is normally maintained at a fixed pressure usually 10 or more pounds less than that of the main reservoir.

(c) The engineer's valve, with its equalizing chamber and reservoir, is connected to the air supply and the brake pipe system, and controls the latter, its function depending upon the position of the handle of the valve. The rotary element of the G6 valve normally has five positions, namely: "running" when air from the main reservoir is permitted to feed through the auto-

matic feed valve into the brake pipe to make up any loss, and to maintain therein a fairly constant pressure; "release" when air from the main reservoir is permitted to flow directly through the brake pipe system to charge it after it has been exhausted; "lap", which, with the two remaining positions, is oppositely disposed from the "release" position, when all ports in the rotary valve are blanketed, there being no feeding of air from the main reservoir into the brake pipe and no escape of air from the equalizing reservoir; "service", when the air supplied from the main reservoir through the feed valve is blanketed from the brake pipe, and air from the latter is permitted to escape into free air through a port controlled by an equalizing piston which is indirectly controlled by the rotary element of the valve through differential air pressures; and finally, "emergency" position in which the air from the main reservoir through the feed valve is blanketed from the brake pipe, but the air in the latter is allowed free escape into atmosphere.

(d) The brake cylinders, in which move, against spring resistance, the pistons and rods connected with the foundation gear of the brake rigging, to force the brake shoes against the car wheels with a varying pressure, depending upon the handling of the engineer's valve.

(e) Auxiliary reservoirs individual to each car, normally charged with air at the same pressure as the brake pipe and through the triple valves supplying air directly to the brake cylinders when required.

(f) Plain or quick-action triple valves individual to each car, these forming the connecting links between the brake pipes, auxiliary reservoirs, brake cylinders and free atmosphere. The construction and functions of these valves are well known to those versed in the art.

(g) Duplex indicating air gauge, one indicator being connected with and showing the air pressure in the main reservoir, and the other connected with and showing the air pressure in the equalizing reservoir, as well, normally, as that in the brake pipe, the latter lagging slightly during reduction.

Various modifications of the above outlined air braking are extant including among others the adjunct of straight air braking and independent locomotive braking with slight changes in the system to meet these adjuncts; also operation of the brake system by electrical control; but for the purpose of this application it is not necessary to describe these in detail although my system is applicable to practically all of them.

All of the operations of braking, whether the making of small or large service applications of air or full emergency applications, are effected by variations of air pressure in the brake pipe, in 5 variable times and amounts depending upon the character of braking, and the release is effected by recharging the brake pipe and bringing its pressure back to normal.

All normal braking is initiated and controlled 10 by the engineer through the engineer's valve, and such normal braking provides when brakes are applied, first, for cutting off connection between the main reservoir and the brake pipe system; second, service application of the brakes, controlled as to rate of application and amount of 15 air reduction in the brake pipe, the time being perhaps half a minute and the reduction anywhere from 3 or 4 to 20 or 25 pounds; and third, emergency application by free exhaust from the 20 brake pipe to atmosphere, the time occupied being but a few seconds, and the resultant more violent braking being the maximum possible under the existing conditions of air pressure in the brake pipe.

25 In service applications on modern systems the engineer does not directly open an exhaust from the brake pipe to atmosphere, but he makes a more or less limited or restricted opening from an equalizing chamber in the bottom of his valve, 30 which is connected with the equalizing reservoir to get a volume of air to handle, and thereby refinement in making air reductions; this reduction of air in the equalizing chamber in turn lifts an equalizing piston by differential air pressure, 35 which when lifted opens the brake pipe to atmosphere through the service port, and when, following the closure of the service controlling port in the engineer's rotary valve, the air on the upper and lower sides of the equalizing piston controlling the service port is equalized in 40 pressure, the brake pipe opening is automatically closed.

In making an emergency application, however, 45 the engineer's valve provides for a direct exit from the brake pipe through a different and larger port, and the reduction of air pressure in the brake pipe is very sudden. It acts first on the nearest car, and then, because not only of the air reduction due to the escape of air through 50 the engineer's valve, but likewise because of the emptying of part of the air of the brake pipe into the brake cylinder through the triple valve when suddenly operated under emergency conditions, there is effected a very quick reduction of 55 air pressure in the second car, and so on in each car of the train in rapid sequence, the application of the brakes under emergency application taking place, not simultaneously (except where 60 electric control is introduced) but in very rapid succession, 40 or 50 cars having emergency brakes applied in a very few seconds.

The construction and operation of the automatic air brake system will be more fully gone into in connection with the drawings.

65 In carrying out my invention I have provided an engineer's automatic valve head which replaces the upper valve body of the usual engineer's valve, being interchangeable upon the lower valve body, and it is the only part of the existing air 70 brake system that is physically altered by the installation of the safety control equipment.

Its mechanism is brought into play through suitable agencies operated when danger conditions exist through instrumentalities on the track 75 and on the train. It does not interfere with any

of the present movements of functions of the engineer's brake valve, so far as manual operation is concerned. Up to the time an automatic application is initiated, and even then, it does not interfere with the manual application of the 5 brakes, though as hereafter pointed out, it tends for a period to oppose the release of the brakes when automatically applied.

The automatic valve head is pneumatically operated but under electric control, for the purpose 10 of placing the engineer's valve handle and rotary valve in a non-charging position, preferably lap position, immediately prior to the automatic venting of the brake pipe, to avoid other than manual releasing of the brakes; and, in one form, through 15 the movement of its motor or driving yoke, it opens an outlet or pilot valve to free atmosphere.

After the engineer's valve handle and rotary 20 valve have been automatically placed in lap position, they are so retained by pneumatic pressure 25 for a period of time co-incident with the energization of a controlling magnet, after which the pneumatic pressure is again released. However, regardless of whether the pneumatic pressure is applied to or released from the brake valve handle 25 and rotary valve, the latter can only be returned to release position by manual operation.

I have further provided means whereby the 30 engineer may, if he has taken advantage of a signal indication—displayed in the cab or from the wayside—within the lapse of time allowed prior to the automatic brake application, by proper action prevent such brake application from taking effect.

For this purpose I have provided electric 35 circuits under manual control of the engineer and effective only prior to the starting of the automatic brake application to remove the automatic brake controlling means from the influence of the track impulse.

40 However, to preclude possible misuse of this brake-preventing or forestalling means by holding or fixing them in their operative position, I have connected them with the engineer's brake handle so as to be effective only in certain of its positions 45 and only under specified conditions, as shall be more fully described in these specifications.

I have also provided means in combination with the manual forestalling means whereby the electric 50 circuits and devices of the automatic brake control equipment will be automatically restored to normal condition without the receipt of any additional track impulse, that is, from an energy source or means within the locomotive itself.

55 Referring to the accompanying drawings in which corresponding parts are designated by corresponding marks of reference:—

Figure 1 is a diagrammatic view of an apparatus 60 embodying my invention, forming the subject-matter of this divisional application.

Fig. 2 is a central vertical section of a standard type of engineer's valve, having mounted thereon in lieu of the standard head my electrically and pneumatically operated brake head.

Fig. 3 is a plan view of the structure shown in 65 Fig. 2 with the cover removed, the valve itself being in running position (having been moved to that position from release) and its pneumatic actuator being inert.

Figs. 4 and 5 are fragmental but corresponding 70 views, the valve in Fig. 4 being now in lap position and its pneumatic actuator energized, while in Fig. 5 the valve has been manually thereafter placed in emergency position.

Fig. 6 is a section through the controlling valve 75

and the pneumatic actuator of the engineer's valve.

Fig. 7 is a plan and elevation of the driving yoke for the engineer's valve.

5 Fig. 8 is a plan and elevation of the driven yoke.

Fig. 9 is a plan and elevation of one of the pistons of the actuator of the engineer's valve.

Fig. 10 is a plan and elevation of all of the connecting rods.

10 Fig. 10a is a plan and elevation of the slack motion switch arm.

Fig. 11 is a diagram on a larger scale than Fig. 1 showing the circuits and certain parts controlled thereby that are shown in Fig. 1. However, Fig.

15 11 shows the control circuit for the controlling valve as arranged on a closed circuit.

Figs. 12 to 14 are fragmental plan views of the engineer's valve with the top removed showing the arrangement of the electric contacts therein

20 for the closed circuit method, whereby Fig. 12 indicates the engineer's valve and associated parts in the running position, Fig. 13 in the position which they assume in case of an automatic brake application and Fig. 14 in the position which they

25 assume when, to forestall an automatic brake application, the engineer's valve is brought from service to lap position.

Fig. 15 shows a control circuit for the arrangement in Figs. 12-14.

30 The automatic brake system with my additions is illustrated in Figure 1. The main reservoir has a pipe connection 2 through which air is delivered into it and compressed therein by an automatically controlled pressure pump, not shown.

35 On the opposite side of the main reservoir is a pipe connection 3, which leads from the main reservoir into pipe 4, which communicates with the passageway 5 in the engineer's brake valve leading to chamber 6 in the top thereof (see Fig.

40 2). The actual construction of a portion of the standard G6 engineer's brake valve, together with my additions thereto, is illustrated in Fig. 2, wherein the rotary valve 7 rests on its seat 8. The casing 9 enclosing the rotary valve and its

45 seat are of a standard construction in respect to passageway 5 and chamber 6.

Considering now Fig. 1, the chamber 6 is shown diagrammatically in the center of the rotary valve

50 7 and the valve seat 8 is shown surrounding the periphery of the rotary element in place of beneath it, the rotary element itself being shown with radiating passages and peripheral cavities in place of the more or less vertical corresponding elements in the physical construction shown

55 in Fig. 2. The valve body 10 (Figure 1) of the engineer's brake valve contains passageways 11, 12, 13 and 14, and an emergency exhaust port 15, all communicating directly with the seat for the rotary valve 7. In this seat is also chamber 16,

60 which has no communication with the atmosphere except through the rotary valve, and a chamber 17, which is in communication with the atmosphere through the emergency exhaust port 15. The passageways 11 and 12 lead respec-

65 tively to and from a feed valve 18. In the bottom of the engineer's valve is an equalizing piston chamber 19. Passageways 13 and 14 lead to and from this chamber respectively at the top thereof. This chamber also at its top is provided

70 with a port 20, and the bounding walls of the chamber constitute a cylinder within which reciprocates an equalizing piston 21. The equalizing piston carries a service exhaust valve 22 which opens and closes a service exhaust port

75 23, leading to atmosphere on the one side, and

communicating with a passageway 24 leading to the underside of the equalizing piston 21 and connecting also with the passageway 12 to the valve and to the brake pipe.

Still considering Figure 1, the rotary valve 7 has three passageways 26, 27 and 28 radiating from chamber 6 and two cavities 29 and 30 on its periphery. Port 29 is the port by which communication is made between the equalizing piston chamber 19 and the equalizing reservoir by means of a pipe 32. The brake pipe is connected with a triple valve by means of a pipe connection 35, and the triple valve is in turn connected with an auxiliary reservoir and a brake cylinder by means of port 39. The triple valve is the connecting link between the brake pipe, the auxiliary reservoir, the brake cylinder and free atmosphere. Its general construction and operation are well known to those versed in the science of braking, and hence no detailed description of its operation is given here.

The spring retracted piston of a brake cylinder is shown at 40, this being the piston which forces the brake shoes against the car wheels, through the foundation gear of the brake rigging, not shown. The duplex gauge 33 above referred to is suitably connected with the main reservoir through a branch from pipe 4 and with the equalizing reservoir through a branch from pipe 32.

The rotary valve 7 is manipulated by means of a spindle 42 (see Figs. 2 and 3), and while this is shown as adapted for use in my invention, it is practically identical with the spindle of the ordinary automatic brake system. The engineer's handle 43 attached to the top of the spindle is the same as that used in the ordinary automatic brake system.

Considering the ordinary practice and operation recited above with reference more specifically to Figure 1, the five positions of the G6 engineer's brake valve—running, lap, service, emergency and release—are indicated as follows:

Running position.—In Figure 1 the rotary valve 7 is shown diagrammatically in running position. The passageway 26 of the rotary element 45 registers with the blind chamber 16 and is blanketed. The passageway 28 is also blanketed; but the passageway 27 registers with the passageway 11 in the valve body, and thus permits the flow of air from the main reservoir into the feed 50 valve 18, and thence into the brake pipe through the passageways 12 and 24. The passageway 12 is in communication with passageway 13 through the cavity 29, thus permitting air from the feed valve to flow into the equalizing piston chamber 55 19 and thence into the equalizing reservoir. Passageway 14 and the emergency port 15 are both blanketed. The same pressure is then maintained in the equalizing piston chamber and the equalizing reservoir as in the brake pipe and beneath the equalizing piston 21, and the service exhaust valve 22 is maintained in its downward position, closing the service port 23. No air escapes from the brake pipe and the brakes are 60 free.

Lap position.—When the brake handle is in the lap position (indicated in Fig. 4), the passageway 26 of the rotary valve registers only with the blind chamber 16 and is blanketed; the passageways 27 and 28 are both blanketed. The 70 passageways 11, 13 and 14, and the emergency exhaust port 15 are also blanketed. There is, therefore, no flow of air from the main reservoir into the brake pipe, or the equalizing piston chamber either directly or through the feed valve, 75

and no flow of air from the equalizing piston chamber. On coming to lap position from service position the service exhaust valve 22, on equalization of pressure due to the drop of pressure 5 in the brake pipe, is moved downward from the position it has at the commencement of the lap position of the engineer's valve by its weight and a slight excess of total pressure of air above the equalizing piston, closing the service exhaust port 23 and after closing, it remains closed as long as lap position is maintained; in coming to lap position from running position the service port 23 is already closed.

Service position.—When the brake handle is in 15 the service position, indicated by dotted lines in Figs. 3, 4 and 5, the rotary valve has rotated further counter-clockwise until the passageway 14 registers with the cavity 30. The passageway 26 registers with the blind cavity 16 and is still 20 blanketed. The passageways 27 and 28 also remain blanketed. As in lap position, the main reservoir is thus cut off from the feed valve, brake pipe, equalizing piston chamber 19 and the equalizing reservoir. The passageway 13 is also blanketed, and since the cavity 30 registers both with 25 passageway 14 and the emergency port 15, the equalizing piston chamber and the equalizing reservoir are open to atmosphere. Service position is normally reached from or through lap 30 position, i. e., a position in which the service exhaust port 23 is closed.

When the engineer makes a service application he reduces the pressure in the equalizing reservoir and the equalizing piston chamber by 35 the number of pounds which he wishes to reduce in the brake pipe, which reduction of pressure will be indicated by one of the hands of the duplex air gauge 33, that hand being black in ordinary practice. As the pressure is reduced in 40 the equalizing piston chamber, the air pressure in the brake pipe, acting on the underside of the equalizing piston raises it, together with the service exhaust valve 22, and opens the service exhaust port 23 to atmosphere, allowing the air to escape therethrough from the brake pipe. The 45 rapidity with which the equalizing piston is thus raised depends upon the rapidity with which the differential between the pressure on top of the equalizing piston and on the bottom of the 50 equalizing piston is made. So long as the equalizing reservoir and the equalizing piston chamber are open to atmosphere by the rotary valve being maintained in service position, the service exhaust port 23 will be held open, provided there 55 is sufficient pressure in the brake pipe to maintain the equalizing piston in its upward position. The resulting drop of pressure in the brake pipe effects a movement of the triple valve to close the opening of the brake cylinder to atmosphere and places the brake cylinder into connection with the auxiliary reservoir so that pressure air therefrom enters the brake cylinder and moves its piston to apply the brakes with increasing pressure. This may continue until what is called 60 the point of equalization is reached, that is, when the air in the brake cylinder and in the auxiliary reservoir is at the same pressure. In ordinary operation, however, the desired service braking is effected before the point of equalization is 65 reached. When the reduction desired in brake pipe pressure has been indicated by the gauge connected with the equalizing piston chamber and the equalizing reservoir, the engineer normally moves his handle into lap position. This 70 movement blankets the ports as heretofore de-

scribed and the venting of air from the equalizing piston chamber is discontinued and when the air in the brake pipe is reduced to the pressure or slightly below the pressure in the equalizing piston chamber, the piston moves downwardly and closes the exhaust port 23. Thus the movement from service position to lap position discontinues the bleeding of the equalizing piston chamber air and places a limit upon the reduction of air in the brake pipe.

While in lap position after having made a service application, there being no port open by which air can enter or leave the brake pipe, the brakes will normally remain applied under this pressure until they have been released either by 15 leakage, or by moving the rotary valve ordinarily into release (or possibly running) position, or until additional pressure has been applied to them by again moving the rotary valve to service or emergency position.

Emergency position.—The emergency position of the engineer's valve handle is illustrated in Fig. 5. This is the extreme braking position of the valve, and it is only possible to come to it from or through service position by moving the 25 rotary valve counter-clockwise from the latter. This leaves the ports in the rotary valve still blanketed, although in a slightly different position, so that there is still no flow of pressure air into the brake pipe and the main reservoir is not 30 bled. The emergency exhaust port 15 is connected through the cavity 29 with the passageway 12 so that a free passage is open from the brake pipe to atmosphere. The exhaust port 15 is also connected by the chamber 17 and the cavity 30 with the passageways 14 and 11. This results in relieving the pressure on the top of the equalizing piston and prevents a possible jamming of the service exhaust valve. If at the 40 time a service application has been effected the rotary valve is moved to emergency position increased braking may be thereby caused.

Release position.—The release position of the engineer's valve handle is indicated by dotted lines in Figs. 3, 4 and 5. After the brakes have 45 been applied it is only possible to come to release position from or through running position, by moving the rotary valve clockwise until passageway 11 is blanketed and air from the main reservoir is prevented from flowing into the feed valve; passageway 26 and cavity 29 both register with chamber 16, cavity 29 also registers with passageways 13 and 12, and passageway 27 registers with passageway 14. Air thus flows freely 50 from the main reservoir through passageways 13 and 14 to the equalizing piston chamber 19 and thence to the equalizing reservoir; and through passageways 12 and 24 into the brake pipe, recharging both the equalizing reservoir and the 55 brake pipe, releasing the brakes in the well known manner.

Release and running positions may be regarded as the charging positions, in that in both of them the main reservoir is either directly or indirectly through the feed valve, in communication with the brake pipe and a transfer of air takes place from the former to the latter to create or maintain therein the proper pressure. In a like manner, service and emergency positions are both braking positions, in that they cause a reduction of brake pipe pressure, and together with lap position may be termed "non-charging" positions, in that in each of these positions communication between the main reservoir, and the 75

brake pipe, the equalizing piston chamber, and equalizing reservoir is cut off.

The construction, function and operation of the triple valves in controlling the application and release of the brakes and of the feed valves in maintaining the differential of pressure between the main reservoir and brake pipe system are in no way changed or affected by the application of my invention; and the function and operation of the engineer's brake valve in manually applying and releasing the brakes when no automatic action occurs are likewise in no way changed or affected by the application of my invention; and the details of these elements are not further illustrated or described herein, as their action is well known.

I have illustrated my invention as superimposed upon the automatic air brake system just described, and as acting through that system in applying the brakes. As illustrated, the rotary valve casing 9, which is substituted for the upper valve body of the ordinary engineer's valve, contains means which normally operate on the spindle 42 to rotate the spindle and its attached rotary valve 7 to a non-charging position, preferably into lap position, this being supplemental to the engineer's handle. In Figures 1 to 5 this valve casing also contains means for effecting the initial outlet of air which effects a drop of pressure in the brake pipe by reducing the pressure in the equalizing reservoir and the equalizing piston chamber, to cause equalizing piston 21 to raise and open the service exhaust port 23.

For convenience reference is made to Patent No. Re. 16,395, July 27, 1926, issued to me on a divisional application of the original application Ser. No. 879,939, now matured into U. S. Letters Patent No. 1,780,148, granted October 28, 1930, for illustration of the lap, release, service and emergency positions of the G6 engineer's valve above referred to; also for a description of the construction and operation of the valve 228 which latter is not claimed herein.

The engineer's automatic valve head, while maintaining in all respects the normal function of the engineer's valve through the movement of the rotary valve therein by the engineer's handle to the various positions of release, running, lap, service and emergency, provides in addition for the automatic application of the brakes, through the usual service exhaust port 23, while at the same time leaving the engineer free to make further manual applications or under certain conditions to release his brakes.

The amount of reduction of brake pipe pressure caused by this automatic application may be limited by the manual clockwise movement of the engineer's valve handle. The part 177 shown in outline has to do with the invention described and claimed in my original application Ser. No. 879,939, now matured into U. S. Letters Patent No. 1,780,148, granted October 28, 1930, above identified, and forms no part of the invention of this divisional application. It is not described or claimed herein and for the purposes hereof pipes 124 and 154 may be considered as in open communication with each other.

The engineer's automatic valve head is electrically controlled and mechanically as well as manually operated and maintains the rotary valve in a non-charging position, e. g., lap position, during the automatic application, so that no air escapes from the main reservoir and enters the brake system therefrom.

This device being interchangeable with the

upper valve body of the ordinary engineer's valve is consequently located in the engineer's cab. While the normal function is as stated above, it in no way prevents the making of manual brake applications through the manual movement of the engineer's valve.

The construction of this valve head can conveniently be understood by referring to Figs. 2 to 10 in connection with Figure 1.

Casing 9 is a flanged cylindrical casting interchangeably bolted to the lower valve body 10 of the engineer's valve. It is partitioned horizontally, and the lower portion constitutes a cylindrical recess, forming the chamber 6 and constituting a cover for the rotary valve 7. The upper portion of the casing comprises an irregular recess with a detachable cover 60 which may be secured in place in any appropriate manner. The valve stem 42 of the rotary valve passes through the partition, which, at this point, is made in the form of and constitutes a bushing 61; thence through an aperture in the cover 60, above which the ordinary brake handle 43 is attached to the stem in the same manner as in the ordinary engineer's valve. The exterior of casing 9 is provided with a notched sector 62, which has the same relative position in respect to the rotary valve and brake handle as in the ordinary engineer's valve.

Cast integral with or fastened to the upper portion of the casing 9, are two motor cylinders 63 and 63', oppositely disposed but with axes parallel to each other. These cylinders are closed at the outer ends but opened at the inner ends, and within them reciprocate suitably packed trunk pistons 66 and 69' respectively, joined by connecting rods 70 and 70' to a driving yoke 71 which is rotatively mounted on bushing 61. Pins 72, 72' project upwardly from the driving yoke and engage the driven yoke 73, which is squared upon the rotary valve stem above the bushing 61 and rotates the valve stem and with it the engineer's brake handle and rotary valve counter-clockwise when driven by the pins 72, 72'. The driving yoke 71 is provided with an adjustable stop 74, 74' adjusted so that the limit of counter-clockwise motion of the driving yoke places the driven yoke in lap position (see Fig. 4), but because the driving yoke engages the driven yoke on one side only the rotary valve is free to be moved manually, through its spindle and the engineer's brake handle, to service or emergency position as may be desired. The motor cylinders and pistons are of such size that while the rotary valve is moved to lap position and maintained there during automatic braking, it is not done so with such force as to make it impractical for the engineer to manually move the rotary valve (carrying with it the two yokes) to either release or running position should he so desire, so that the action of the motor cylinders is subordinated to this manual operation.

The motor cylinders are pneumatically connected behind their respective pistons by pipes 75 and 75' which connect through a three way coupling with a pipe 76 leading to a controlling valve 80, through which provision is made to connect the motor cylinders either with atmosphere direct through the upper part of the valve, or to pressure air through the lower part of the valve, supplied through a pipe 89, a throttling valve 90 and a pipe 91 leading from the throttling valve to the chamber 6, as is shown in Figs. 2 and 3. As shown in Figure 1 the pipe 91 is directly connected with the pipe 4, a strainer 88

is interposed on one side of the throttle and a capacity chamber 89' on the other side. The construction of the controlling valve 89 is illustrated in Fig. 6. It consists of a double face section 81 with a connection 82 from its center to pipe 76. In this section are centered two suitably faced poppet valves 83 and 84 which are oppositely disposed, and whose valve stems, passing through guiding apertures in section 81, are in contact at their ends, which are oppositely rounded. The lower of these valves 84 is normally held against its valve seat 84' by spring 85, reinforced by air pressure when the system is charged, and hence is normally closed; and in this position it lifts the upper poppet valve 83 from its seat 83' and raises plunger 85'. The contacting faces of the upper valve 83 and its plunger are also oppositely rounded. Conversely, when the upper poppet valve 83 is pressed downward by the plunger 85' against its valve seat 83' and is closed, the lower poppet valve is forced downward into its guide 86 and is opened. Both valves are enclosed in housings, in the upper of which provision is made for exit to atmosphere through ports 87, 87, and with the lower of which the throttling valve 90 and any capacity pipe or chamber if needed, is conveniently connected, as by pipe 89. To permit free circulation of air when the valves are opened their stems are flattened on three sides, as indicated and the valves fit loosely in their respective housings.

The controlling valve, therefore, comprises in brief, two oppositely disposed poppet valves, arranged in tandem, one of which is normally opened and the other of which is normally closed. The rounded surface of the valve stems above mentioned eliminate possibly improper seating of the valve faces. The position of the valve shown in Fig. 6 is its running position, i. e., the valve is in readiness for operation to admit pressure air to the motor cylinders for an automatic application of the brakes. When at rest no air from the main reservoir passes through the valve to the motor cylinders 68, 68', but air from the motor cylinders is allowed free escape to atmosphere past poppet valve 83 through the ports 87, 87. When the automatic braking is initiated the poppet valves are moved from their upper or running position to their lower position, and the passageway from pipe 76 to atmosphere is then closed so that no air escapes from the motor cylinders, but air at main reservoir pressure is admitted to the motor cylinders through the open poppet valve 84.

The throttling valve 90, which is also illustrated in Fig. 6 as an adjustable needle valve, governs the rate of supply of pressure air from the chamber 6 to the controlling valve and thence to the motor cylinders. In Figure 1 the pipe 89 is illustrated as being enlarged, forming a capacity reservoir 89'. This capacity reservoir merely assures ample volume of air to act on the pistons 69 and 69' when the controlling valve 90 is thrown from normal to braking position, so as to promptly overcome the locking of the engineer's handle on the sector notches. It permits a more liberal opening of the throttle valve without the danger of throwing the rotary valve past lap position.

A strainer or dust separator 88 should be provided in the air line preceding the throttling valve 90. This is indicated diagrammatically in Figure 1.

An arm 95 lies over the plunger 85' of the controlling valve and has one end pivotally mounted

at 95' to the casing 9, and its other end is pivotally and adjustably attached to an armature 96 through a link 97 and a screw piece 98. The armature is actuated downward by a solenoid 99 which, as illustrated in Figs. 2 and 3, is rigidly mounted in the upper portion of the casing 9, but the armature is normally held up in the position illustrated in Fig. 6 by the spring 85 of the controlling valve, reinforced by air pressure when the system is charged.

Three terminals 101, 102, and 103 are mounted on an insulating block 104 contained in the upper portion of the casing 9; two of these terminals 101 and 102 are electrically connected in a battery circuit in a manner later to be described. Two copper strips 105 and 105', are also mounted upon this insulating block and vertically disposed thereon. The coil of the solenoid 99 is electrically connected between the battery lead terminal 101 and copper strip 105, the other of the strips being electrically connected with the other battery lead terminal 102. Consequently when the strips are bridged and there is a difference of potential between the terminals 101 and 102, the solenoid will be energized, its armature drawn downward and the controlling valve moved from inert free air (upper) position to active power supply (lower) position, and there maintained until the solenoid is deenergized, when it is returned to running position and raises the armature as above described.

On the same bushing 61 which carries the driving yoke 71, and below it, is rotatively mounted a slack-motion switch comprising a sleeved arm 110, having a slot 111 in which engages a pin 112 carried by and projecting downward from the driven yoke 73. At the outer end of the arm is an insulated section carrying two independent spring contacts 113, 113', electrically connected and lying in a vertical plane. These spring contacts, for a certain arc of movement, press upon the copper strips 105, 105', and constitute the means of bridging them, and thereby completing the solenoid control circuit.

The length and position of the copper strips 105 is such that when the engineer's brake handle has been placed in release position they are bridged by spring contacts 113, 113', and that this bridging will continue during counterclockwise movement of the slack-motion switch by the brake handle until the brake handle has reached a position between lap and service position.

The length of the slack-motion switch slot 111 illustrated is such that the engaging pin 112 has free movement therein through a distance equal to its travel in moving the engineer's brake handle from running to lap position, but no further.

The copper strips 105, 105' are, therefore, always bridged by spring contacts 113, 113' in manual release and running position, but never in service or emergency positions. They are bridged in lap position when that position is approached from release or running positions but not when approached from emergency or service positions.

The third of the terminals 103 is electrically connected with the copper strip 105' with which the solenoid coil is connected. Rotatably mounted upon this terminal, and electrically connected with it, is a spring retracted arm 115 carrying a spring contact 116, which is normally out of contact with terminal 102 as illustrated in Fig. 3. The upper portion of pin 72' is covered with insulation, and arm 115 lies in its forward path of motion; when struck thereby it presses its spring contact 116 against terminal 102 and constitutes a second means of completing the circuit through

the solenoid. Its closing position is illustrated in Fig. 4, where the position of the parts is such that the bridging of the copper strips 105, 105' by spring contacts 113, 113' has not been broken at the time contact is made between the spring contact 116 and the terminal 102, while in Fig. 5 the solenoid circuit is only completed through the spring contact 116 and terminal 102. The contact 116 is diagrammatically represented on Fig. 1 by the contact finger 116^a movable with the yoke 71.

It will be noted that the closure of the circuit by the follow-up spring contact 116 can be effected only by the movement of the driving yoke 15 under air pressure to put the valve in lap position, and that this closure is maintained throughout all movement of the engineer's valve to service or emergency position after it has been automatically thrown to lap position.

In addition to the function of the driving yoke 71 above described, it has the further function of opening a pilot valve to atmosphere causing a reduction of pressure in the equalizing chamber and equalizing reservoir. This pilot valve 119, which is illustrated as a suitably faced spring closed poppet valve seats against its head 120, which is adjustably secured into the upper portion of the casing 9 adjacent to the stationary portion of the stops 74, 74' to permit regulation of the extent of valve opening. Its stem 121 passes through a guiding aperture at its head, and to assure a free passage of air when the valve is opened, is flattened on three sides as indicated at 122, 122. It is in the line of forward travel of a lug 123 carried on the driving yoke 71, by which means the pilot valve is opened. In this connection the stop 74, 74' has the additional function to that above mentioned of preventing the jamming of the pilot valve head 120 by receiving the thrust from the driving yoke 71. (See Figs. 4 and 5.) The chamber of the pilot valve connects with the equalizing reservoir and equalizing piston chamber 19 by pipes 124, 154 and 32 and is illustrated as so connected through an additional part 177, which as above set forth may be disregarded for the purposes of this divisional application, pipes 124 and 154 being assumed as in direct communication with each other.

The pilot valve 119 is so positioned and adjusted that when the driving yoke completes the movement of the rotary valve to lap position, it opens the pilot valve the desired amount to effect the operation of the equalizing piston 21 through reduction of air pressure above it, so that any appreciable clockwise movement of the driving yoke from its then position, as for example when the engineer's handle is moved from lap position toward running or release position, permits the pilot valve to close instantly under its own pressure.

We shall now proceed to describe the electromagnetic impulse transmitting and receiving means as well as the electric control devices and circuits of my automatic train brake system.

Placed along the track are track magnets 320 controlled by traffic conditions from suitable relays through the wayside signals or by any other suitable means so that current is supplied thereto and the magnet excited when a caution or danger condition exists.

An inductive receiver 400 cooperates with the track magnets and when it passes an excited track magnet an impulse is transmitted to the receiver.

Connected in series with the receiver 400 is detector relay 410 and a regulating resistance

413. An armature 411, which is normally in its lower contacting position, thereby closing a circuit at the contact 426, is attracted upon the receipt of a track impulse and starts operation of the further control devices, as will be seen hereafter.

A commutator comprising a split metal shell 490 mounted on a cylinder 491 of insulating material which is rotatable in the direction of the arrow forms part of these controlling devices. The shell of the commutator is stepped as indicated diagrammatically in Fig. 1 to insure variably timed electrical engagement with five contact fingers 492, 493, 494, 495 and 496. The commutator is normally at rest in the position shown in Fig. 1 and rotary motion is given to it under circumstances and in a manner later to be presented.

A battery 420 is connected at one end directly with a contact finger 493 which is maintained in constant contact with shell 490 except during the period when it passes over the split or break across it. This break is made narrow, its width, however, being sufficient to prevent bridging by the contact fingers in passing thereover. The detector relay 410 and winding of the receiver 400 are connected in series through a regulating resistance 413.

The contact finger 492 is connected with the clear signal lamp 422 and its shunt resistance 422', and the contact finger 494 is connected with the danger signal lamp 423 and its shunt resistance 423'. These two lamp circuits are joined, and connected through the maintaining coil 433 and the shunt thereto formed by the armature 411 and contact 426 of the detector relay 410 and the armature 452 and contact 451 of the maintaining coil in series with each other, to the battery through a hand switch 497.

The non-inductive resistance normally in circuit, that is, when the apparatus is at rest, is the clear lamp 422 and its shunt 422'; but when the cylinder is rotated from its normal position the danger lamp 423 and its shunt 423' form such a resistance. The shunts to the lamps are for the purpose of maintaining continuity of those parts of the circuits in the event of lamp failure. The normally closed clear signal circuit can be traced as follows: Starting from battery 420, by contact 493, shell 490, contact finger 492, lamp 422 and its shunt resistance 422', relay detector armature 411, contacts 426 and 451, armature 452, and hand switch 497 to the battery. An inappreciable part of the current therein also passes through the maintaining coil 433. If the circuit is broken at either contact 426 or 451 all of the then existing current will flow through the maintaining coil.

Whether or not the current from the battery passes through the maintaining coil when shunted, as long as the finger 492 is in contact with the shell 490 the clear signal lamp will be illuminated.

On the rotation of the commutator the shell passes out of contact with the finger 492, and after a slight interval makes contact with the finger 494. This breaks the normally closed clear signal circuit and establishes the danger signal circuit through the danger signal lamp 423 and its shunt. The breaking of the first mentioned normally closed circuit deenergizes the maintaining coil 433 and allows the shunt to it to be re-established.

The operating coil 460 is connected with the battery 420 on one side directly, and on the other

side through the contact 453 and the armature of the maintaining coil when that coil is energized. The spring-retracted armature 464 of the operating coil 460 forms a stop for the commutator, as will be hereinafter described.

The fourth contact finger 495 makes contact with the shell 490, simultaneously with the finger 494. It is connected directly with the audible danger signal 498, here illustrated as a buzzer or bell, the circuit through which is completed by a fixed connection to the hand switch and thus to the battery.

The finger 496 makes contact with the shell 490 as the commutator continues in its rotation, thereby closing a circuit for the coil 99. This circuit includes the normally closed spring contacts 113, 113' (shown in Figure 1 as a single contact 113) and in multiple thereto the normally open follow-up contact 116 of the engineer's automatic 20 valve head, (shown in Fig. 1 as 116a).

The circuit through the operating coil 460 which has been traced previously does not include any of the five contact fingers enumerated. The circuit for coil 460, which has already been 25 traced, becomes energized following the energizing of the maintaining coil 433.

While any suitable driving apparatus can be used for rotating the commutator which will preferably rotate its rotation at a uniform and desired speed, the apparatus illustrated in the 30 type of construction now under consideration comprises in part a spring driven mechanism similar in general construction and action to the mechanism of some alarm clocks. The commutator is rigidly mounted on a suitably supported shaft 510 driven from a shaft 511 through bevel gears at like axle speeds. Upon the shaft 511 is also rigidly mounted a releasing disc 512 with a depression on its periphery. The spring retracted 40 armature 454 of the operating coil is mounted on one end of an extended arm 513 which is centrally pivoted and carries on the opposite end from the armature a small wheel 514 which in the normal or at rest position of the apparatus lies in the depression of the releasing disc. The arm 513 also carries a fixed pawl 515 which in the 45 normal position of the apparatus engages in the teeth of high speed wheel 516 connected by a train of gears with the shaft 511 and arrests the rotation of the commutator. When the wheel 514 is lifted from the periphery of the releasing disc 512 the pawl is out of locking engagement and the train of gears is released.

The clockwork, being locked in a state of 55 equilibrium, is set in operation by the energizing of the operating coil 460, which draws down its armature 464, clears the pawl 515, and raises the wheel 514 from the depression in the disc 512. The rotation of the commutator now being begun, the wheel then rides along the periphery of the disc and holds the pawl out of locking engagement, but when the commutator and the disc have made one complete rotation, assuming that the operating coil 460 is, by that time, deenergized, the wheel will drop into its depression and the pawl will return to its holding engagement. Deenergizing of the operating coil 460 prior to the time of one revolution of the commutator will not permit the pawl to be returned to its holding engagement because of the fact that the wheel 514 is held up in riding on the disc.

Operation

Normally the equipment is in the condition as 75 indicated in Fig. 1. The detector relay being nor-

mally inert, its armature 411 is in the lower contacting position. The armature 452 of the maintaining coil 433 is also normally down and the series combination of these two armatures forms a shunt across the coil 433 which is thus practically deenergized. The clear light 422 is maintained energized through its circuit from battery 420, through contact finger 493, commutator shell 490, contact finger 492, lamp 422, through armature 411, contact 426, contact 451, armature 452, switch 491, back to battery. The circuits of the danger lamp 423 and alarm 498 are broken at the contact fingers 494 and 495, respectively. The circuit of the magnet 99 is broken at the contact finger 496 and the circuit of the operating coil 460 is broken at the contact 463 so that both coil 99 and coil 460 are deenergized.

When a track magnet 320 at the end of the block is energized due to the presence of a train (represented in Fig. 1 by car truck 316) in the 20 block in advance, it induces a current in the receiver 400 upon its passage thereby. This energizes coil 410 which now attracts its armature 411, thereby breaking the contact 426 and the shunt to the maintaining coil 433 and shifting 25 the circuit through the visible clear signal 422 from the shunt around the maintaining coil into the maintaining coil itself. Simultaneously, the contact 451 opens, thus preventing, so long as the circuit is complete, the shunt of the maintaining coil being again re-established by the de-energizing of the detector coil and the closing of the contact 426; the circuit of the operating coil 460 at the contact 463 is also closed, energizing the operating coil, which at once releases the 30 clockwork of the commutator and starts the rotation of the commutator in a manner already described.

After the track magnet has been passed and the impulse in the receiver has died away, the 40 detector relay coil is again deenergized and armature 411 drops.

As the commutator further progresses in its rotation there is set up a condition whereby the contact finger 492 of the visible clear signal 422 45 is broken, but the contact fingers 494 and 495 of the visible danger signal and audible danger signal 498, respectively, have not yet made contact. The maintaining coil 433 is thus again deenergized, thereby dropping its armature 452 50 and breaking the circuit of the coil 460 at the contact 463, but, as already explained, this does not stop the rotation of the commutator. The dropping of the armature 452 supplementing the dropping of the armature 411 re-establishes the 55 shunt across the maintaining coil.

Upon further travel of the commutator the contact fingers 494 and 495 are brought into contact with its shell, contact finger 496 still being idle. Circuit of the visible danger signal 423 60 is now completed through the shunt to the maintaining coil. Also the circuit of the audible danger signal 498 is completed and the engineer is warned both by visible and audible signals of danger ahead and the necessity of taking fore- 65 stalling action to prevent an automatic brake application.

Upon further travel of the commutator it 70 brings the contact finger 496 into contact with the shell 490, and should the engineer not fore-stall at the proper time (by an action later to be described) it completes the circuit of the solenoid 99 of the engineer's valve head, thereby causing an automatic application of the brakes as follows. As can be readily seen from Fig. 3 75

which shows the engineer's valve in its normal running position, as the solenoid 99 has its circuit completed it will draw downward its armature 96 and place the controlling valve 80 in its power supplying position by means of operating arm 95. Pressure air will then be admitted through the controlling valve, as above described, into the motor cylinders 68, 68', and will thrust the pistons outward and rotate the driving yoke 71 counterclockwise. The pins 72, 72' on the driving yoke will then engage and rotate the radial arms of the driven yoke, which in turn will move the rotary valve to lap position, and finally the driving yoke at the limit of its motion will open the normally closed pilot valve 119. The opening of the pilot valve in turn automatically effects the application of the brakes by reducing pressure in equalizing reservoir and equalizing piston chamber.

The motion of the engineer's handle and rotary valve is opposed by two forces, one, the friction and compression of the spring tongue in the engineer's handle on the notch sector 62, which may be considered about the same whatever the air pressure, and the other the friction of the rotary valve on its face, and of the rotary valve spindle against its air seat, which friction will vary about directly as the air pressure. These forces are to be taken into consideration in adjusting the throttling valve 90, the adjustment of which should be such that while the rotary valve is automatically moved to lap position, it is not done so with such a speed that its momentum carries it beyond that position.

However, should the engineer be alert and take advantage of the signal indication he may prevent such automatic brake application by breaking the circuit of the coil 99 at the contacts 113, 113' (illustrated as a simple contact 113 in Fig. 1) of the engineer's automatic valve head. As has already been described, the contacts are broken if the engineer's brake valve handle is moved to service or emergency position or is brought to lap position approached from service or emergency position.

The engineer thus may forestall an automatic brake application, but only before the automatic brake application has started, as once the coil 99 has been energized the brake valve is moved by automatic action into lap position and thereby closes the follow-up contact 116 in the engineer's brake valve head, this contact 116 being in shunt to the contact 113 and thus closing the circuit of coil 99 independently of contact 113.

Upon further rotation of the commutator the circuits of the danger light 423, the alarm 498 and the coil 99 will be broken at the contact fingers 494, 495, 496, and when the commutator has completed its rotation the circuit of the clear light 422 will again be made at the contact 492. In this position the wheel 514 of the armature arm of the operating coil 460 drops into the depression in the releasing disc 512, which permits the pawl 515 to lock the high speed gear and arrest the movement of the commutator in the normal running position.

It will be seen, therefore, that upon completion of movement of the commutator the electric control of the equipment is automatically restored to normal whether an automatic brake application has taken place or has been forestalled.

If a forestalling action has been taken, no pneumatic part of the automatic brake equip-

ment having been actuated, all of the equipment will thus be restored automatically to normal.

If an automatic brake application has taken place deenergization of the solenoid 99 will relieve the armature 96 from the magnetic pull, thus permitting it to be raised to its top position by the controlling valve 80, which then cuts off pressure air from the motor cylinders and then opens to atmosphere. This, however, causes no movement of the rotary valve from its then lap position, and, consequently, the brakes once automatically applied are held so until manually released by the engineer's brake handle being moved, ordinarily, into release position. This not only releases the brakes but restores the motor pistons and driving yoke to the position illustrated in Fig. 3, in readiness for a second automatic application.

It should be noted that when the parts of the automatic valve head are free from automatic action the engineer has the entire sweep of his sector, and with perfect freedom and without interference can manipulate his brake handle and apply and release his brakes in the ordinary manner; also, that during automatic braking the rotary valve is capable of manual movement to either extreme position of its sector, its movement toward release position being opposed and hindered by the pressure in the motor cylinder 68, 68', while perfect freedom is given such movement to a further brake applying position.

While the construction of apparatus and the connections of the brake operating circuits as shown in Figs. 1 to 9 embody a normally open circuit method of operation, it is evident that the closed circuit method may be used by obvious changes in any part of or in the whole system. Such is indicated in Fig. 11, which shows the electric circuits only, and so far as track and detector and allied circuits are concerned, is the same as Fig. 1.

In Fig. 11 the commutator shell 490 is changed in form on its right-hand end so that solenoid 99 is in a normally closed circuit and hence is energized by current from battery 420. The solenoid when energized, instead of pulling down the lever 95 (see Fig. 6) to operate the controlling valve 80, holds it up, the lever being pulled by its operating spring when released against the plunger 85' of the controlling valve 80. Such release of the lever will occur whenever the current in coil 99 is broken from any cause; normally, this happens when, as the commutator 491 advances in its rotation, contact finger 496 breaks contact. (It should be noted in Fig. 11 that the commutator is shown as having just started its rotation due to the receipt of a track impulse.)

To effect the same control of the action of the solenoid 99 as in the open circuit method through the movement of a slack motion switch by the rotation of the spindle of the engineer's brake valve, it is necessary to have the slack motion contacts 113 close a maintaining shunt upon the finger 496 when a manual brake application is made and the follow-up contact 116 opens the same shunt circuit when an automatic application is made.

This is illustrated in Figs. 12 to 15. The contacts 105a and 105a' are now bridged by the contact 113 in the service and emergency positions and in the lap position when approached from service position, and electric connection is normally maintained through contact spring 116a, but interrupted when an automatic brake application takes place.

From the foregoing description it will appear that I have provided for train control apparatus whereby the receiver and the detector will transmit an impulse to the locomotive equipment every time an active track element is passed, setting up an alarm to indicate the fact that the track element is alive and that the apparatus is intact. The forestalling thus restricts itself only to the prevention of a brake application and not to the receipt of a track impulse.

It also appears that to prevent an automatic brake application forestalling action has to be taken within a given limited period of time, after the expiration of which the forestalling means are ineffective.

It further appears that by connecting the forestalling means to the operating handle of the engineer's brake valve and making said means effective under conditions and in positions in which the handle can not be kept unduly long without the engineer losing control of the train, I have made it unfeasible to maintain the forestalling means for an unlimited time in their operative position.

I have also shown automatic restoration means whereby the automatic brake controlling device will be restored to normal without the receipt of any further track impulse in case a brake application has been forestalled, and partly automatically and partly manually in case an automatic application has been received.

The foregoing detailed description has been given for clearness of understanding, and no undue limitation should be deduced therefrom but the appended claims should be construed as broadly as permissible in view of the prior art.

Having thus described my invention, what I claim as new and desire to secure by Letters Patent is:

1. In an automatic train control system the combination of trackway means controlled according to traffic conditions, a coil-surrounded vehicle element registering with the trackway means as the vehicle proceeds along the track, said vehicle element and trackway means forming a charged inductive couple under danger conditions, means responsive to changes in the electromotive force of the coil, means controlled by said responsive means for effecting an alarm and initiating an automatic brake action, manually operable means for forestalling the automatic brake action, and means for automatically restoring the responsive means to normal condition without further registration of the vehicle element with trackway means.

2. In an automatic train control system the combination of trackway means controlled according to traffic conditions, a coil surrounded vehicle element registering with the trackway means as the vehicle proceeds along the track, said vehicle element and trackway means forming a charged inductive couple under danger conditions, means responsive to changes in the electromotive force of the coil of the vehicle element, means controlled by said responsive means for initiating an automatic brake action, manually operable means for forestalling the automatic brake action, means for restoring the responsive means to normal condition without manual action and without additional registration of the vehicle element with trackway means, and means for producing an alarm signal intermediate the actuation of the responsive means and the initiation of said automatic brake action.

3. In an automatic train control system the

combination of trackway means controlled according to traffic conditions, a coil-surrounded vehicle element registering with the trackway means as the vehicle proceeds along the track, said vehicle element and trackway means forming a charged inductive couple under danger conditions, means responsive to changes in the electromotive force of the coil of the vehicle element, means controlled by said responsive means for effecting an alarm and initiating an automatic brake action, means for automatically restoring after a time interval the first responsive means to normal condition without additional registration of the vehicle element with trackway means, and means for forestalling the automatic brake action during the interval of initiation of the change in and restoration to normal of the responsive means.

4. In an automatic train control system, in combination, track impulse devices and vehicle carried brake control apparatus, said apparatus comprising an electro-pneumatic valve and an energizing circuit therefor, de-energization of the electro-pneumatic valve in response to a track impulse causing an automatic brake application, a manually operable device for forestalling by prior operation the de-energization of the electro-pneumatic valve and a normally closed circuit-breaker, opening of which prevents the forestalling device from being effective in maintaining the electro-pneumatic valve energized.

5. In an automatic train control system, in combination, track impulse devices and vehicle carried apparatus, said apparatus comprising an electro-pneumatic valve and an energizing circuit therefor, said electro-pneumatic valve being de-energized in response to a track impulse, and a manually operable device effective to prevent de-energization of the electro-pneumatic valve while energized, but not re-energizing said electro-pneumatic valve after it responded to de-energization thereof.

6. In an automatic train control system comprising trackway means in each block controlled according to traffic conditions and a vehicle carried element registering inductively with the trackway means as the vehicle moves along the track, the combination of an electro-pneumatic valve for effecting an automatic brake application, a circuit-controlling device therefor intermediate the vehicle element and the electro-pneumatic valve, means for both changing the condition of the intermediate controlling device from, and then restoring it to, normal condition in response to a single registration of the vehicle element and trackway means, and means for forestalling the operation of the electro-pneumatic valve during the interval of initiation of change in and restoration to normal of the control circuit.

7. In an automatic train control system the combination of an electro-pneumatic valve for initiating an automatic brake application, an energizing circuit for said valve, with impulse transmitting means along the track to open the circuit of the electro-pneumatic valve, manually controlled forestalling means for maintaining said valve energized in spite of receipt of a track impulse said manual means effective only if operated prior to the initiation of the automatic braking, and means for preventing the manually controlled forestalling means from being effective after the automatic brake application has started.

8. In an automatic train control system com-

prising trackway means in each block controlled according to traffic conditions, and a vehicle element registering inductively with the trackway means as the vehicle moves along the track to form a magnetic couple, the combination of an electro-pneumatic valve for effecting an automatic brake application, a controlling device therefor intermediate the vehicle element and the pneumatic valve, means for manually forestalling the operation of the valve, and means for both first changing the intermediate controlling device from, and then restoring it to, normal condition in response to a single registration of the vehicle element and trackway means.

15. 9. In an automatic train control system comprising trackway means in each block controlled according to traffic conditions, and a vehicle element registering inductively with the trackway means as the vehicle moves along the track to form a magnetic couple, the combination of an electro-pneumatic valve for effecting an automatic brake application, a maintaining circuit for the pneumatic valve and a circuit-controlling device therefor intermediate the vehicle element and the pneumatic valve, means for both first changing the intermediate controlling device from, and then restoring it to, normal condition in response to a single registration of the vehicle element and trackway means, and means for forestalling the operation of the electro-pneumatic valve during the interval of the initiation of change in and restoration to normal condition of the circuit-controlling device.

20. 10. In an automatic train control system the combination of trackway means controlled according to traffic conditions, a vehicle element registering inductively with said trackway means and influenced thereby in case of danger conditions, means responsive to a change in the condition of the vehicle element to control an electro-pneumatic valve to initiate an automatic brake application, means initiated by the same trackway means for automatically resetting said influence responsive means, and means under manual control for preventing an automatic brake application.

25. 11. In an automatic train control system the combination of a trackway means controlled according to traffic conditions, a vehicle element registering inductively with said trackway means, a normally energized electro-pneumatic valve for effecting when deenergized an automatic brake application, means responsive to a change in the circuit of the vehicle element upon registering with a single trackway element, to both change and restore the circuit of said electro-pneumatic valve, and manual means for nullifying the effect of the initial change in said circuit.

30. 12. In an automatic train control system comprising trackway means under control of traffic conditions, a vehicle element registering inductively with the trackway means, a circuit controlling device associated with the vehicle element, an electro-responsive valve controlled thereby for initiating an automatic brake application, and means initiated by a change in the vehicle element on registration with and passage over a single track element to first change from and then to restore to normal condition the controlling circuit of the electro-pneumatic valve, and a manually controlled means to prevent an automatic brake application if actuated prior to the initiation of said brake application.

35. 13. In an automatic train control system comprising trackway means under control of traffic

conditions, a vehicle element registering inductively with the trackway means, a circuit-controlling device associated with the vehicle element, an electro-pneumatic valve controlled thereby for initiating an automatic brake application, means initiated by a change in the vehicle element on registration with and passage over a single track element to first change from and then to restore to normal condition the controlling circuit of the electro-pneumatic valve, and manually operated means for temporarily annulling the action of the electro-pneumatic valve controlling the automatic brake application intermediate the initiation of change in and restoration to normal of the device controlling the electro-pneumatic valve because of the passage of the vehicle element over a single trackway element.

40. 14. In an automatic train control system, trackway elements active under adverse traffic conditions, and vehicle apparatus comprising means to inductively register with the trackway elements and to be influenced thereby when the trackway elements are active, brake apparatus and a normally energized electro-pneumatic valve for the control of said apparatus to cause an automatic brake application when said vehicle element registers with an active trackway element, and manual means which if brought into an operative position will prevent de-energization of the electro-pneumatic valve, but will not re-energize it after it has responded to de-energization.

45. 15. In an automatic train control system, vehicle carried apparatus comprising normally inactive brake applying means including an engineer's valve, and a normally energized electro-pneumatic valve to cause when de-energized movement of said engineer's valve and an automatic service application of the brakes, and manually operable means effective to prevent de-energization of said electro-pneumatic valve but not effective to re-energize it after said engineer's valve has responded to de-energization of said electro-pneumatic valve.

50. 16. In an automatic train control system comprising trackway means active in case of adverse traffic conditions and a vehicle element registering inductively with the trackway means as the vehicle moves along the track, brake apparatus on the vehicle and a normally energized electro-pneumatic valve for the control thereof, said valve effecting when de-energized an automatic brake application, a normally closed contact to control the energization of the electro-pneumatic valve and adapted to be opened by the registration of the vehicle element with active trackway means, manual forestalling means, which when brought into an operative position maintain the electro-pneumatic valve energized in spite of the opening of said contact, provided they have been brought into such position before response of said electro-pneumatic valve to the opening of said normally closed contact, said forestalling means if maintained in their operative position causing abnormal condition of the brake apparatus.

55. 17. In an automatic train control system, in combination, trackway elements and vehicle apparatus comprising a normally energized brake initiating pneumatic valve and an electric relay controlling it, an alarm and a receiving element which upon inductive registration with a single track element produces successively a change in the electric condition of the controlling relay, then an alarm, then the restoration of the relay to normal and manually operated means for

maintaining the brake initiating valve in an inactive condition during the successive changes.

18. In a train control system, the combination with car-carried means comprising an electro-responsive brake control device and its armature to control a normally inactive brake-setting appliance which when active causes an automatic application of the brakes, of influence-communicating means at predetermined control points 5 on the track which in traffic conditions in advance are dangerous always operate the brake control device and its armature and thereby tend to operate the brake-setting appliance, a circuit controller actuated if an automatic application takes place, 10 and manual forestalling means to prevent operation of the brake-setting appliance provided the circuit controller has not been actuated in spite of the operation of the brake controlling device. 15
19. In a train control system of the inductive 20 type, car-carried apparatus comprising a group of electro-responsive devices and electric circuits governed by same, these devices and circuits being interlocked so as to cause a successive operation of the devices; a normally closed circuit-controller controlled by the last electro-responsive device, and manually operable means to prevent operation of the last electro-responsive device in spite of the operation of the other electro-responsive devices said manual means being effective only if said circuit-controller is in its normal condition.

20. In a train control system the combination with trackway devices of car-carried apparatus comprising a plurality of electro-responsive devices said devices always changing their electric condition when a trackway device set for danger condition is passed, and another electro-responsive device change in the electric condition of which can be prevented by manual forestalling 35 means, said last named electro-responsive device controlling a circuit-controller which when operated prevents the manual forestalling means from being effective.

21. In an automatic train control system a 40 brake control device inactive when energized, a main energizing circuit and an auxiliary circuit for said device, manual means to close the auxiliary circuit and means to prevent the auxiliary circuit from being closed if the brake control device is in its active condition.

22. Vehicle-carried equipment for automatic 45 train control comprising a normally energized electrically controlled operable device, a main circuit and an auxiliary circuit therefor, said auxiliary circuit maintaining said device energized but not being capable of re-energizing it after it has been operated, and manual means to close said auxiliary circuit.

23. In a train control system, vehicle-carried 50 means comprising brake-applying apparatus and a normally energized solenoid which when deenergized causes actuation of the brake-applying apparatus, an energizing circuit for the solenoid including a normally closed contact of a time-controlled contactor; a normally open energizing circuit including a contact which when manually closed prevents deenergization of said solenoid, and a circuit-controller, operation of which prevents the closing of the auxiliary circuit.

24. In an automatic train control system for 55 railway vehicles, brake control apparatus on the vehicle having an energizing circuit, traffic-controlled means partly on the vehicle and partly on the track for interrupting said energizing circuit, 70 a normally open auxiliary maintaining circuit

including the brake control device, manually operable means for closing said maintaining circuit at one point, and means responsive to the operation of the brake control device for interrupting the auxiliary circuit at another point 5 when said device is operated.

25. In a train control system, a normally energized brake control device on a vehicle, means for controlling said device from the trackway in accordance with traffic conditions, a circuit controller influenced from the trackway to deenergize the brake control device, a normally open auxiliary energizing circuit to maintain said device energized in spite of the opening of said circuit controller, said auxiliary circuit comprising in series a normally open and a normally closed contact, manually operable means for closing the normally open contact, and means to open the normally closed contact upon operation of the device. 20

26. In a train control system car-carried apparatus and trackway devices cooperating in case of dangerous traffic condition, the car-carried apparatus comprising an electro-responsive brake control device having a normally closed maintaining circuit opened upon cooperation with the trackway devices, an auxiliary circuit to maintain the brake control device energized in spite of such cooperation, a time mechanism which following a fixed time interval after its actuation 30 operates a circuit controller in the maintaining circuit of the brake control device, said auxiliary circuit being ineffective to energize the brake control device after said circuit controller has been operated.

27. In an automatic train control system, brake apparatus comprising the usual engineer's valve, a normally energized electro-pneumatic valve de-energization of which results in movement of the engineer's valve and in an automatic service 40 brake application, trackway means to cause de-energization of the electro-pneumatic valve in case of danger conditions, and manual forestalling means to prevent de-energization of the electro-pneumatic valve but incapable of re-energizing said electro-pneumatic valve after said engineer's valve has responded to de-energization of said electro-pneumatic valve. 45

28. Vehicle-carried equipment for the control of the brakes thereof comprising, a normally energized normally inactive electrically controlled brake control device, a normally closed main circuit for said device controlled in accordance with traffic conditions in advance of the vehicle, an auxiliary circuit for said device closed at one 55 point when said device is in its normal inactive condition, and manual means for closing said auxiliary circuit at another point.

29. Vehicle-carried equipment for the control of the brakes thereof comprising, a normally energized normally inactive electrically controlled brake control device, a normally closed main circuit for said device controlled inductively from the trackway in accordance with traffic conditions in advance of the vehicle, an auxiliary circuit for 65 said device closed at one point when said device is in its normal inactive condition, and manual means for closing said auxiliary circuit at another point.

30. Vehicle-carried equipment for the control 70 of the brakes thereof comprising, a normally energized normally inactive electrically controlled brake control device, a normally closed main circuit for said device opened if traffic conditions in advance of the vehicle are dangerous, an aux- 75

iliary circuit for said device closed at one point when said device is in its normal inactive condition but normally open at another point, and manual means for closing said auxiliary circuit 5 at said another point.

31. Vehicle-carried equipment for the control of the brakes thereof comprising, a normally energized normally inactive electrically controlled 10 brake control device, a normally closed main circuit for said device controlled inductively from the trackway and opened if traffic conditions in advance of the vehicle are dangerous, an auxiliary circuit for said device closed at one point when said device is in its normal inactive condition 15 but normally open at another point, and manual means for closing said auxiliary circuit at said another point.

32. Vehicle-carried equipment for the control of the brakes thereof comprising, a normally energized normally inactive electrically controlled 20 brake control device, a normally closed main circuit for said device controlled in accordance with traffic conditions in advance of the vehicle, a normally open auxiliary circuit for said device 25 closed at one point when said device is in its normal inactive condition, and a contact operated by movement of an engineer's brake valve on the vehicle for closing said auxiliary circuit at another point.

30 33. Vehicle-carried equipment for the control of the brakes thereof comprising, a normally energized normally inactive electrically controlled 35 brake control device, a normally closed main circuit for said device controlled in accordance with traffic conditions in advance of the vehicle, an auxiliary circuit for said device closed at one point when said device is in its normal inactive condition, and a contact closed when an engineer's brake valve on the vehicle is moved to 40 a service brake applying position for closing said auxiliary circuit at another point.

34. In an automatic train control system, vehicle carried apparatus including a normally energized normally inactive device for controlling 45 the movement of the train, means partly on the vehicle and partly on the track for deenergizing said device under adverse traffic conditions in advance of the vehicle, and manually operable means effective when operated to prevent deenergization 50 of said device but ineffective to reenergize it after it has once been actuated.

35. In an automatic train control system, vehicle carried apparatus including a normally energized normally inactive device for controlling 55 the movement of the train, means partly on the vehicle and partly on the track inductively cooperating for deenergizing said device under adverse traffic conditions in advance of the vehicle, and manually operable means effective when operated to prevent deenergization of said device but ineffective to re-energize it after it has once been actuated.

36. In an automatic train control system, vehicle carried apparatus including a normally energized normally inactive device for controlling 60

the movement of the train, means partly on the vehicle and partly on the track for deenergizing said device under adverse traffic conditions in advance of the vehicle, and an engineer's brake valve on the vehicle effective when operated to prevent deenergization of said device but ineffective to re-energize it after it has once been actuated.

37. In an automatic train control system, vehicle carried apparatus including a normally energized normally inactive device for controlling 10 the movement of the train, means partly on the vehicle and partly on the track for deenergizing said device under adverse traffic conditions in advance of the vehicle, and an engineer's brake 15 valve on the vehicle effective when operated to a service brake applying position to prevent deenergization of said device but ineffective to re-energize it after it has once been actuated.

38. In combination, vehicle control apparatus 20 on a vehicle including a normally energized normally inactive vehicle control device, means which although only momentarily actuated will deenergize said device for an appreciable period of 25 time and actuated under danger traffic conditions in advance of the vehicle, and manually operable means effective to prevent deenergization of said device but ineffective to re-energize said device after it has once been actuated.

39. In combination, vehicle control apparatus 30 on a vehicle including a normally energized normally inactive vehicle control device, means on the vehicle inductively controlled from the trackway which although only momentarily actuated will deenergize said device for an appreciable 35 period of time and actuated under danger traffic conditions in advance of the vehicle, and manually operable means effective to prevent deenergization of said device but ineffective to re-energize said device after it has once been actuated.

40. In combination, vehicle control apparatus 40 on a vehicle including a normally energized normally inactive vehicle control device, means which although only momentarily actuated will deenergize said device for an appreciable period 45 of time and actuated under danger traffic conditions in advance of the vehicle, and circuit controlling means controlled by movement of an engineer's brake valve on the vehicle effective to prevent deenergization of said device but ineffective to re-energize said device after it has once been actuated.

41. In combination, vehicle control apparatus 55 on a vehicle including a normally energized normally inactive vehicle control device, means which although only momentarily actuated will deenergize said device for an appreciable period of time and actuated under danger traffic conditions in advance of the vehicle, and circuit controlling means effective when an engineer's brake 60 valve on the vehicle is moved to the service brake applying position to prevent deenergization of said device but ineffective to re-energize said device after it has once been actuated.

FRANK J. SPRAGUE. 65
